ATTORNEY

UNITED STATES PATENT OFFICE.

GUSTAF L. FINSTROM, OF CHICAGO, ILLINOIS.

PORTABLE BED.

1,367,955.

Specification of Letters Patent.

Patented Feb. 8, 1921.

Application filed September 11, 1919. Serial No. 323,124.

To all whom it may concern:

Be it known that I, GUSTAF L. FINSTROM, a citizen of the United States, residing at Chicago, in the county of Cook and State 5 of Illinois, have invented certain new and useful Improvements in Portable Beds, of which the following is a specification.

My invention relates to folding, collapsible or contractible beds, cots and the like 10 and has practical reference to the conveniently portable types thereof. The object of my invention is to provide a bed of this type which may be constructed so that it may be reduced to substantially "suit case" 15 space dimensions when not in use and yet be firmly supported and supporting.

With these general objects in view my invention consists in the novel construction, combination and arrangement of parts, all 20 as hereinafter described in detail, illustrated in the accompanying drawing and more particularly pointed out in the appended claims.

In the drawing—

25 Figure 1 is a front elevation of the bed in its closed or compact form.

Fig. 2 is an end view of the form of the bed shown in Fig. 1.

Fig. 3 is an elevation, partly broken away, 30 of the bed drawn out, extended or made ready for service.

Fig. 4 shows the bed partly pushed together or restored to its Figs. 1 and 2 position.

35 Fig. 5 is an enlarged section of a broken away upper part portion of one of the series of substantially identical outer legs to which the bed-bottom clamps are pivoted, taken substantially on the line 5—5 on Fig. 3.

40 Fig. 6 is a section on an enlarged scale taken substantially on the line 6—6 of Fig. 5.

Fig. 7 is a section on an enlarged scale 45 taken substantially on the line 7—7 of Fig. 3, of a broken away portion of the clamp bars 20 and 21.

The several views illustrate a simple and inexpensive embodiment of my invention adapted for such material as soft wood, the 50 bulk of which may be reduced by perhaps one-half by a judicious selection of material and by a suitable modification of the details of construction. In said views the frame of the bed is substantially a series of 55 intermediate inner legs 2 for each side of the bed (only one of two identical sides being

shown), pivoted to a corresponding series of outer legs 3. The inner member at the foot end of the bed is designated separately by the numeral 4, being distinguished from 60 the intermediate inner members in that it is longer than the latter, and with its companion member 4 carries a cross bar and clamp that engages the foot end of a bed bottom 5 which may be a sheet of canvas, 65 woven wire, or other suitably flexible material. Each of the outer members at the head end of the bed is designated by the numeral 6. The members 6 are longer than the members 3, being extended in length to 70 support the pillow portion or pillow support at the customary inclination or elevation. The members 3 carry the supports for the side edges of the bed; the members 4 support the foot end; the members 6 75 support the head end of the bed and the members 2 are free of bed-bottom attachments. The outer legs attached to the inner legs 4 are separately designated by the numeral 7. The leg 7 is pivoted at 8 and 9 80 to legs 2 and 4, respectively and each of the legs 3 is pivoted at 10, 11 and 12 to three inner legs 2. The legs 6 are each pivoted at 13 and 14 to two inner legs 2.

The outer legs 3 and 6 support the side 85 edges of the bed bottom 5 through a series of clamps each of which consists of a pair of members 15 and 16 that are secured to each other by screws or bolts 17 and are supported pivotally upon a screw, bolt or 90 pivot 18 which passes through a bore in the member 15 and has, in the present embodiment, a head 19 that is countersunk into the inner face of said member 15, as shown in Figs. 1 and 5. 95

The upper ends of the members 3 and 6 are beveled parallel to the bed bottom when the bed is extended as in Fig. 3. The members 4 at the foot-end of the bed are connected at their upper ends by a combination bed-bottom clamp and cross bar or brace that consists of a pair of bars 20 and 21 that, like the smaller side clamps, are secured or drawn toward each other by screws or bolts 22 and clamp therebetween 100 the foot end edge of the bed bottom 5, as shown in Figs. 2, 3 and 4. Sections of the side edges of the bed bottom 5 are in like manner clamped between the members 15 and 16. Each of the inner legs 2 is connected 105 with its companion member 2 at the opposite side of the bed by an upper cross bar 23 with its companion member 2 at the opposite side of the bed by an upper cross bar 23

and a lower cross bar 24, the ends of which may be secured to said inner legs in any suitable manner, or by a mortise and tenon joint suggested by dotted lines in Fig. 1. 5 The inner legs thus form a series of substantially rigid frames, indicated in Fig. 1, extending transversely of the bed. These frames being pivoted at a plurality of points and to a plurality of outer legs provide firm support for the latter against 10 sidewise angular movement of the outer and inner legs. These connections between the inner legs may be varied in numerous ways, preferably to the end of leaving packing 15 space below the folded bed bottom as shown in Fig. 1. The upper ends of the elongated outer legs 6 are beveled as at 25 and said upper ends are hinged at each side at 26 and 27 to a pillow frame, board or support 20 28. The side clamp members 15 and 16 lie upon and parallel with the legs 3 and 6, as indicated in Figs. 2 and 4, when the bed is "closed." The pillow portion 28 is, when the bed is thus closed, folded over and 25 upon the legs and may be hooked, tied, or otherwise secured to the cross bar and clamp 20, 21 and be provided with a carrying handle if desired. The pillow portion thus turned over as a cover may well serve as a 30 seat or table when the bed is not in use. The legs, braces and clamps are, when the bed is closed, stacked compactly upon each other and in such a manner as to provide 35 spaces or compartments 29, 30 and 31, as indicated in Fig. 1, which are approximately two-thirds of the area included within the outer boundary lines of the folded or closed bed. These spaces may be 40 varied as to size relative to each other and as to number by any desired rearrangement of cross-bars between the legs 2 at opposite sides, and are adapted to receive pillows and bed covers, or such articles as are usually carried in a traveler's bag or case. If 45 the height of the bed is reduced in height to occupy the vertical dimension of an ordinary suit case, say, fourteen or fifteen inches, there will still be ample room for a light bed cover and pillow, as the folded bed bottom 5 when made of canvas requires 50 but a small amount of space. The head-end of this bed bottom is shown tacked onto the board 28, 32 indicating the fastenings. 55 As shown in Fig. 3 the side-clamps 15, 16 for the side-edges of the bed bottom or sheet 5 are limited in length to leave spaces therebetween sufficient to facilitate said clamps assuming the angular relations shown in Fig. 4 which represent either

the opening or closing positions of the parts. 60 Said side-clamps tend to assume their zig-zag positions to fold the bed-bottom in like manner, when one end of the bed is pushed toward the other end, the weight of the sheet between the clamp on the leg 65 7 and the leg 4 depressing the end of the clamp directed toward said leg 4 thereby elevating the opposite end and therewith the end adjacent to said opposite end of the clamp on the leg 3 which is adjacent to the 70 leg 7, and so on. The opening and closing of the bed is therefore practically an instantaneous operation free from the requirement of manipulations which would be involved if the bed bottom and side clamps 75 required a series of individual adjustments to form the zig-zag folding of the parts upon each other.

I claim as my invention—

1. The combination of a series of legs 80 arranged substantially parallel to each other for each side of a bed, another similar series of legs which are pivoted to and cross the first mentioned legs, a series of bed bottom clamps pivoted on the latter and 85 engageable with the side edges of a bed bottom, fastening means for the end-edges of said bed bottom, and a bed-bottom carried by said fastening means and legs.

2. The combination with a flexible bed 90 bottom, of a plurality of substantially rigid frames arranged transversely of said bed bottom, a plurality of bed bottom supporting legs pivoted to opposite sides of said frames, a bed bottom clamp pivoted to each 95 of said legs and engaging sections of the side edges of said bed bottom, a pillow portion pivoted to two of said legs and supporting the head portion of said bed bottom, and means on one of said frames which 100 support the foot end portion of said bed bottom.

3. The combination with a flexible bed bottom, of a series of relatively movable clamp members, a series of legs upon which 105 said clamp members are mounted, said clamp members engaging side portions of said bed bottom, means engaging the head and the foot portions of said bed bottom mounted on the legs at the head and foot 110 of said bed, and connections between said legs on which the latter are movable to lie compactly upon each other or to assume extended or spaced apart relations.

In testimony whereof I have hereunto 115 signed my name.

GUSTAF L. FINSTROM.
